UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

DUMP-CAR DOOR.

Original applications filed August 30, 1919, Serial No. 320,792 (now Patent No. 1,380,055, dated May 31, 1921), and April 7, 1921, Serial No. 459,305. Divided and this application filed June 22, 1922. Serial No. 570,245.

To all whom it may concern:

Be it known that I, GARTH G. GILPIN, a citizen of the United States, residing at Riverside, in the county of Cook and State 5 of Illinois, have invented certain new and useful Improvements in Dump-Car Doors, of which the following is a specification.

My invention relates to railway cars of the drop-bottom or dumping type, and has 10 for its object to provide an improved sheet metal door having reinforcements which gives the door the desired strength and rigidity, and which, furthermore, do not hinder the free discharge of the cargo when the 15 door is so arranged on the car that the load passes over it in discharging. The doors of cars of the dumping type are usually made of sheet metal and are subjected to severe 20 shocks and pressures due to the impact of the cargo in loading and the weight of the material on the door, and other causes, and these shocks and pressures tend to deflect 25 and warp the doors so that in time they are likely not to properly close. Any considerable warping may also interfere with the movements of the door.

The invention consists of the new and improved constructions, arrangements and devices, to be hereinafter more specifically described and claimed, for carrying out the 30 above stated objects and such other incidental objects as will appear from the following description.

The invention is illustrated in certain preferred embodiments, in the accompanying drawing, wherein

Fig. 1 is a fragmentary plan view of a railway car of the "general service" type, provided with a drop-bottom panel or door 40 made in accordance with my invention;

Fig. 2 is a vertical section taken on line 2-2 of Fig. 1, and

Fig. 3 is a plan view of a modified construction of door panels.

Like characters of reference designate like parts throughout the several figures of the drawing.

Reference will be made first to Figs. 1 and 2 of the drawing wherein I have shown a door panel constructed in accordance with my invention applied to a car of the "general service" type. It will be obvious, how-

ever, that these door structures shown in these figures are not limited in their use to cars of this particular type. In Figs. 1 and 55 2 the side wall of a railway car is indicated by the reference character 10, the center sill structure by the reference character 11, and the cross members of the underframe by the reference characters 12, 12. 60

The door consists of a sheet metal panel 13, provided with downwardly projecting flanges 14. These flanges are preferably formed integral with the body of the sheet by pressing the margins of the sheet outwardly from the body portion so as to form a continuous rigidifying rib around the margins of the sheet. The door may be hinged to the body of the car in any suitable manner. In the drawing I have shown it 70 hinged to the center sill structure 11 by a pair of hinges 15, 15, the strap portions 16, 16 of which extend substantially across the door panel. The hinge straps may be secured to the door in any suitable manner, 75 for example by rivets 17. In order to provide the marginal portions of the door, outside the hinges, with the necessary rigidity to resist the tendency which the door may have to sag under the pressure of the cargo, 80 or to be distorted by the various other stresses to which it is subjected, and to also reinforce and rigidify the structure throughout, the door panel is formed with a plurality of corrugations 18 arranged preferably 85 in two sets 19, 19^a across the hinge straps 16, 16. The corrugations of each set are parallel one to another and extend diagonally outward from the hinged edge and middle portion 20 of the panel toward the lateral 90 edges of the door. The corrugations 18 are pressed, preferably so as to project above the plane of the door and terminate within the edges of the panel at points adjacent the marginal flange 14. By forming the door 95 panel with diagonally disposed corrugations, of the character shown in the drawing, it is effectively reinforced without such reinforcements materially interfering with the discharge of bulk material such as sand, gravel, coal or the like, when the doors are lowered to their discharging position.

In Fig. 3 I have shown a modified construction of door panel in which the corru-

gations, designated 18^a, instead of being arranged in two sets of different angular disposition, as in Fig. 1, all extend in the same diagonal direction. That is, the corrugations 18^a in the arrangement are preferably parallel with each other, and extend diagonally across the door sheet from one margin to another. The marginal portions and hinge strap constructions of the modification shown in this figure may be substantially the same as the corresponding constructions shown in Figs. 1 and 2. This form of the invention is not specifically claimed herein, being the subject matter of 15 a divisional application filed October 10, 1922, Serial No. 593,505.

This application is a division, through my co-pending application Serial No. 459,305, filed April 7th, 1921, of my application for 20 Letters Patent Serial No. 320,792 filed August 30, 1919, now patented as No. 1,380,055, May 31, 1921.

I claim:

1. A sheet metal door for a railway car 25 of the dumping type having hinge members extending across the under side of the door and provided with a plurality of diagonally disposed corrugations which extend from the hinged edge of the door toward the lateral 30 and opposite edges thereof, certain of said corrugations crossing said hinge.
2. A sheet metal door for a railway car of the dumping type, provided with hinges having hinge members extending across the 35 under side of the door so as to strengthen the same, and formed with two sets of diagonally disposed corrugations which extend from the hinged edge of the door toward

the lateral edges and the edge opposite said hinged edge.

3. A sheet metal door for a railway car of the dumping type adapted to be hinged to the bottom of the car and formed with two sets of diagonally disposed corrugations which extend from the hinged edge and the 45 center portion of the door outwardly toward the lateral edges and the edge opposite said hinged edge.

4. A sheet metal door for a railway car of the dumping type adapted to be hinged to the bottom of the car and formed with two sets of diagonally disposed parallel corrugations which extend from the hinged edge and the center portion of the door outwardly toward the lateral edges and the edge 55 opposite said hinged edge.

5. A sheet metal door for a railway car of the dumping type adapted to be hinged to the bottom of the car, provided with angular marginal flanges and formed with two sets of diagonally disposed corrugations which extend from the hinged edge and the center portion of the door outwardly toward the lateral edges and the edge opposite said hinged edge.

6. A sheet metal door for a railway car of the dumping type adapted to be hinged to the bottom of the car comprising a panel formed with a plurality of corrugations which terminate within the edges of the panel and extend from the hinged edge and center portion of the panel outwardly toward the lateral edges and the edge opposite said hinged edge.

GARTH G. GILPIN.
